UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

No. 908,173.

Specification of Letters Patent.

Patented Dec. 29, 1908.

Application filed March 21, 1908. Serial No. 422,503.

To all whom it may concern:

Be it known that I, JESSE G. VINCENT, a citizen of the United States, residing at Detroit, in the county of Wayne and State of Michigan, have invented certain new and useful Improvements in Adding and Listing Machines, of which the following is a specification.

In machines of this character it is common to employ a series of spring-actuated hammers to do the printing and to provide for automatically tripping off hammers from left to right for the purpose of printing ciphers in decimal places of any amount where no digits occur. It is also common practice to interrupt the tripping off of hammers when the machine is to be used for simultaneously printing two or more separate columns. Reference may be had to the Gooch Patent No. 825,205, July 3, 1906, which shows an adding and listing machine of the well-known Burroughs type (see Burroughs Patents Nos. 504,963 and 505,078, September 12, 1893) modified to provide for interrupting the automatic tripping of hammers at will. Such a machine is commonly termed "split and normal" because of its capability for operating either with all of the hammers related for the automatic tripping from left to right or operating in the so-called "split" or divided state so that ciphers will not be printed between items or amounts of separate columns. The Gooch invention provides for locating the point of split variously but not for changing the location at will by the user of the machine through manipulation of devices on the exterior of the machine though this latter expedient has heretofore been practiced in what is known as a "variable split and normal" machine.

The present invention relates to this last-mentioned advanced type of adding and listing machine and involves a new and simplified mode of arriving at the desired result which gives opportunity for considerably reducing the number of component parts in the "variable split and normal" mechanism and also facilitates the assembling of parts, besides providing a construction which is thoroughly reliable.

With such objects in view the invention consists in certain novel features of con-

struction and combinations of parts the essential elements whereof are recited in the appended claims and a preferred form of embodiment of which is clearly illustrated in the accompanying drawings and described in detail hereinafter.

Of said drawings Figure 1 represents in sectionalized right side elevation a sufficient portion of an adding and listing machine of the well-known Burroughs type having embodied in it the present invention, to show the relation of the latter to the regular parts of the machine; Fig. 2 is a fragmentary top plan view of the machine; Fig. 3 is a left side elevation partly in section of the particular portion of the machine where the present invention takes effect, this view representing the relation of parts when the so-called "split" has been established at a certain point and the operating handle of the machine has been drawn forward; Fig. 4 is a similar view illustrating the changed effect when the machine is "normal" or operating without a "split"; Fig. 5 is a front elevation of that department or section of the machine to which the present invention is applied, some parts being broken away to disclose others to the rear and some parts appearing in cross-section; Fig. 6 is a detail sectional view taken substantially on the line 6—6 of Fig. 5; Fig. 7 is a front elevation of indexing devices on the exterior of the machine; and Fig. 8 is a section on the line 8—8 of Fig. 7.

The present invention has to do particularly with that portion of the machine commonly termed the "printing section." In the regular Burroughs machine it is located at the rear and comprises suitable supporting side plates, pivoted hammers 715 striking rearwardly, pivoted hammer-driving levers 716 carrying studs 753 engaging cam slots 7 in the hammers, springs 780 attached to said levers and tending to impel them in a direction to deliver the hammer blow, pivoted latches 717 normally restraining said levers, pivoted spring-actuated pawls 718 for lifting said latches, an oscillating bail carrying said pawls and composed of side arms 711 and a cross rod 704, and a restoring bail for the levers 716, said bail comprising side arms 712 and a cross rod 709.

The numeral 611 designates the usual rack

and type-carrying levers, shouldered obliquely as at 6 to cooperate with the tails of the pawls 718 in a well-known manner for preventing a pawl from taking effect upon the associated latch unless the type-carrier has moved far enough to present one of the digit types at the printing line.

It will be understood that as in the regular Burroughs machine depression of amount keys followed by drawing forward of the operating handle will cause the type-carrying levers to assume positions for presenting at the printing line type corresponding with the depressed keys and that any type-carriers or levers associated with banks of keys in which none have been depressed will move far enough to present at the printing line the cipher types, the type-carrying levers having the usual slot and pin connection with the racks which permits movement of levers to that extent, though corresponding racks are not released by depression of any amount keys. Of course ciphers should not be printed to the left of the highest digit of the amount but should be printed in decimal places to the right where no digits occur. In the Burroughs machine the latches 717 are usually formed with lateral projections or tails, the tail of a latch overlapping the adjacent latch to the right so that the lifting of any latch by its pawl 718 will result in the lifting of all latches to the right so that the hammers will all be fired notwithstanding that in some or all decimal places to the right no digital types have been set up and consequently the pawls 718 are disabled.

In the present construction the latches 717 are not formed with lateral projections or tails and the successive release of hammers from left to right is not brought about through coaction of latches. Instead the levers 716 are modified in form and permitted movement in excess of that required to deliver the printing below, and these levers act upon the latches to secure the successive tripping or displacement of the same. The latches themselves are somewhat modified in form as compared with those ordinarily employed in a Burroughs machine, said latches being abbreviated below the cross rod 700 on which they are pivoted and presenting forwardly-facing edges *a* adapted to be acted upon by rounded noses *b* of forwardly and upwardly projecting branches 716^a of the levers 716. These lever branches or horns are offset at their upper ends as best shown in Fig. 5, the letter *c* designating an obliquely-extending portion between the body of each branch and the nose *b* thereof. Thus each lever 716 except that one furthest to the right is adapted to act upon the latch of the adjacent lever. The cam slots 7 of the hammers 716 have dwell extensions 7^a so that the levers 716 may partake of movement independently of the

hammers after having imparted to the latter movement sufficient for the printing below. It is this excess movement of the levers independently of the hammers which causes the noses *b* of the lever branches or horns to act upon the latches.

It will be seen that with a construction such as last-mentioned described the successive tripping or latches for cipher printing can be interrupted by preventing a certain hammer-driving lever from partaking of the excess movement referred to. Ordinarily in a Burroughs machine movement of the levers 716 is limited by the contact with the rock shaft 703 to which the bail 704-711 is secured. In the present construction the levers likewise abut that shaft but the levers will be cut away or the shaft reduced so as to provide for the excess movement of the levers. In Fig. 4 the parts are illustrated positioned as when the machine is "normal" and the operating handle has been drawn forward. It will be noted that the left hand lever 716 has come up against the shaft 703 and that its stud 753 has passed into the dwell extension 7^a of the hammer cam-slot and that the nose *b* of the lever branch or horn has acted against the edge *a* of the latch to the right and lifted that latch. The left hand type-carrying lever 611 is here represented as positioned for presenting the cipher type and consequently the pawl 718 has been displaced in the forward swing of the bail 704-711. It will be understood that the restoring bail 709-712 retreats far enough to permit such movement of the hammer-driving levers as here illustrated. Said bail is as usual oscillated through the medium of a link 729 which connects it with a crank plate 823 on the usual rock shaft 800.

For the purposes of the present invention the rock shaft 703 is hollow as illustrated in Fig. 6 and longitudinally slotted as shown at *d* in said figure. A collar *e* surrounds this shaft and is connected by a pin running through said slot with a rod *f* sliding in the bore of the rock shaft, the collar being slideable on the exterior of said shaft. This collar is of the proper thickness to prevent excess movement of a hammer-driving lever. Hence it will be seen that by positioning the collar in line with any one of these levers movement of that lever sufficient to trip the adjacent latch will be prevented. Thus a "split" can be established at any desired point. Fig. 3 shows the collar positioned in line with one of the levers 716 and the parts are represented as they would appear with the operating handle drawn forward. When the left hand lever was released by reason of the lifting of its latch by the pawl 718 (the type-carrying lever having moved to position for setting up a digit type) it acted as usual to fire the hammer but by reason of encountering the collar *e* was prevented from partak- 130

ing of excess movement. Consequently the stud 753 did not pass into the dwell extension of the cam slot and the nose *b* did not act against the edge *a* of the adjacent latch to the right.

The following described means are employed for controlling the position of the sliding collar: Between collars *g* pinned to the rod *f* there is loosely confined the bent and apertured end of an irregular-shaped link *G*, best seen in Fig. 5, said link at its left hand end being jointed to a crank arm *g*² secured to the inner end of a rock shaft *G'* (Fig. 1) which projects at the lower front part of the machine and which has affixed to it a handle crank arm *g*². The latter is adapted to move over a segmental plate *H* secured on the exterior of the machine and inscribed with numerals from 1 to 8 (Fig. 7) with any one of which numerals the pointed end of the arm *g*² may register. The plate is apertured as shown at *h* and the arm *g*² carries a knob *h*² slidably mounted in a boss on said arm and thrust inwardly by a spring *h*³ (Fig. 8). The stem of this knob projects for engagement with one or another of the openings *h*. The arm *g*² preferably carries a roller stud *g*³ occupying an arc-shaped slot *h*⁴ in the plate *H*, for guiding purposes.

When the machine is to operate as "normal" *i.e.*, without interruption of the hammer-tripping action the index arm or pointer *g*² must be at the zero position, the stem of the knob *h*² being engaged with the opening *h* furthest to the left and the pointer end of the arm *g*² registering with the *O* inscription on the plate. This means that the link *G* and the rod *f* and consequently the collar *e* will all be in the extreme positions to the left and the collar beyond the plane of the first hammer-driving lever and so of course out of line with all the hammer-driving levers so that each can partake of movement sufficient to trip the adjacent latch except of course the lever associated with the units bank of keys. Should it be desired for example to establish a split between the fourth and fifth banks counting from the left the knob *h*² will be drawn out and the arm *g*² swung to the right until the pointed end of the same registers with the numeral 4 on the plate *H* as illustrated in Fig. 7. The release of the knob permits said arm to become interlocked with the plate at the proper adjustment to hold the collar *e* directly in line with the fourth hammer-driving lever counting from the left as illustrated in Fig. 5. The effect will be to prevent this lever from partaking of the excess movement necessary to trip the adjacent latch. Consequently the successive tripping will stop with the printing in the fourth bank and assuming that no keys are depressed in any banks to

the right of the split the hammers associated with those banks will none of them be released as is illustrated in Fig. 5.

Of course it will be understood that the split can be established at any point by simply moving the handle crank arm *g*² and locating it by the inscriptions on the plate *H*. In order to assist the user in properly indexing said arm a plate *H'* (Fig. 2) is secured on the keyboard just below the amount keys and inscribed with numerals from 1 to 8 at points in median lines of the key banks or rows. The user will then determine by consulting the keyboard just where he desires to establish the split and will turn the handle crank arm until it registers with the numeral on the plate *H* corresponding with the numeral on the plate *H'*, which numeral on the latter plate occurs in a median line of the banks of keys on opposite sides of the point where the split is desired. The plate *H'* also has a *O* inscription located to indicate that when the handle crank arm is registering with the corresponding inscription on the plate *H* the keyboard can be used to its full capacity in listing a single column of items.

While the above-described construction is well calculated to thoroughly fulfill the objects primarily stated yet it is to be understood that this construction is susceptible of modification without departure from the scope of the present invention, which can be carried out in various ways.

What is claimed is:

1. In a machine of the character described, the combination of hammers and their respective driving means, individual restraining devices therefor adapted to be successively tripped thereby, and means for preventing such tripping at one or another point at will.

2. In a machine of the character described, the combination of hammers and their respective driving means, individual restraining latches therefor adapted to be successively tripped thereby, and means for preventing such tripping at one or another point at will.

3. In a machine of the character described, the combination of hammers and their respective driving means, individual restraining devices therefor adapted to be successively tripped thereby, means for preventing such tripping at one or another point at will, and means for tripping the restraining devices independently of the hammers' and their driving means.

4. In a machine of the character described, the combination of hammers and their respective driving means, individual restraining latches therefor adapted to be successively tripped thereby, means for preventing such tripping at one or another point at will,

and means for tripping the restraining latches independently of the hammers and their driving means.

5. In a machine of the character described, the combination of hammers and their respective driving means having movement in excess of that required to deliver the printing blow, individual restraining devices therefor adapted to be successively tripped thereby through such excessive movement thereof, and means for eliminating such movement to prevent such tripping at one or another point at will.

6. In a machine of the character described, the combination of hammers and their respective driving means, having movement in excess of that required to deliver the printing blow, individual restraining devices therefor adapted to be successively tripped thereby through such excessive movement thereof, and an obstructing device adjustable to prevent such excessive movement at one point or another at will.

7. In a machine of the character described, the combination of hammers and their respective driving means arranged side by side, and having movement in excess of that required to deliver the printing blow, individual restraining devices for the same, adapted to be successively tripped thereby, and an obstructing device movable transversely of the series of hammers and driving means and adapted to prevent the excessive movement thereof at one point or another.

8. In a machine of the character described, the combination of spring-drawn hammer levers, latches for restraining the same respectively and adapted to be successively tripped by adjacent levers, and means for preventing such tripping at one point or another at will.

9. In a machine of the character described, the combination of spring-drawn hammer levers, latches for restraining the same respectively and adapted to be successively tripped by adjacent levers, means for preventing such tripping at one point or another at will and means for tripping the latches independently of the levers.

10. In a machine of the character described, the combination of spring-drawn hammer levers, having movement in excess of that required to print, latches normally restraining said levers respectively and adapted to be tripped by adjacent levers through the excessive movement thereof, and means for obstructing one lever or another to prevent the tripping.

11. In a machine of the character described, the combination of spring-drawn hammer levers, arranged side by side and having movement in excess of that required to print, latches normally restraining said levers respectively and adapted to be tripped by adjacent levers through the excessive

movement thereof, and an obstructing device movable transversely of the series of levers and adapted to prevent the excessive movement of one or another of the same at will.

12. In a machine of the character described, the combination of spring-drawn hammer levers, arranged side by side and having movement in excess of that required to print, latches normally restraining said levers respectively and adapted to be tripped by adjacent levers through the excessive movement thereof, a shaft extending transversely of said series of levers, and a collar sliding on the shaft and adapted to prevent excessive movement of one or another of the levers.

13. In a machine of the character described, the combination of spring-drawn hammer levers, arranged side by side and having movement in excess of that required to print, latches normally restraining said levers respectively and adapted to be tripped by adjacent levers through the excessive movement thereof, an obstructing device movable transversely of the series of levers and adapted to prevent the excessive movement of one or another of the same at will, and indexed manipulating means for moving said obstructing device.

14. In a machine of the character described, the combination of spring-drawn hammer levers, arranged side by side and having movement in excess of that required to print, latches normally restraining said levers respectively and adapted to be tripped by adjacent levers through the excessive movement thereof, a shaft extending transversely of said series of levers, a collar sliding on the shaft and adapted to prevent excessive movement of one or another of the levers, and indexed manipulating means for moving said obstructing device.

15. In a machine of the character described, the combination of spring-drawn hammer levers, arranged side by side and having movement in excess of that required to print, latches normally restraining said levers respectively and adapted to be tripped by adjacent levers through the excessive movement thereof, a shaft extending transversely of said series of levers, a collar sliding on the shaft and adapted to prevent excessive movement of one or another of the levers, a rock shaft, a link cranked to the same and connected with said collar, a handle on the rock shaft, and an index plate.

16. In a machine of the character described, the combination of a series of pivoted hammers with cam slots and dwell-extensions thereof, a series of spring-drawn levers with studs engaging said cam-slots and adapted to traverse the dwell-extensions thereof permitting continued movement of the levers after the hammers have struck,

UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

No. 908,173.

Specification of Letters Patent.

Patented Dec. 29, 1908.

Application filed March 21, 1908. Serial No. 422,503.

To all whom it may concern:

Be it known that I, JESSE G. VINCENT, a citizen of the United States, residing at Detroit, in the county of Wayne and State of Michigan, have invented certain new and useful Improvements in Adding and Listing Machines, of which the following is a specification.

In machines of this character it is common to employ a series of spring-actuated hammers to do the printing and to provide for automatically tripping off hammers from left to right for the purpose of printing ciphers in decimal places of any amount where no digits occur. It is also common practice to interrupt the tripping off of hammers when the machine is to be used for simultaneously printing two or more separate columns. Reference may be had to the Gooch Patent No. 825,205, July 3, 1906, which shows an adding and listing machine of the well-known Burroughs type (see Burroughs Patents Nos. 504,963 and 505,078, September 12, 1893) modified to provide for interrupting the automatic tripping of hammers at will. Such a machine is commonly termed "split and normal" because of its capability for operating either with all of the hammers related for the automatic tripping from left to right or operating in the so-called "split" or divided state so that ciphers will not be printed between items or amounts of separate columns. The Gooch invention provides for locating the point of split variously but not for changing the location at will by the user of the machine through manipulation of devices on the exterior of the machine though this latter expedient has heretofore been practiced in what is known as a "variable split and normal" machine.

The present invention relates to this last-mentioned advanced type of adding and listing machine and involves a new and simplified mode of arriving at the desired result which gives opportunity for considerably reducing the number of component parts in the "variable split and normal" mechanism and also facilitates the assembling of parts, besides providing a construction which is thoroughly reliable.

With such objects in view the invention consists in certain novel features of con-

struction and combinations of parts the essential elements whereof are recited in the appended claims and a preferred form of embodiment of which is clearly illustrated in the accompanying drawings and described in detail hereinafter.

Of said drawings Figure 1 represents in sectionalized right side elevation a sufficient portion of an adding and listing machine of the well-known Burroughs type having embodied in it the present invention, to show the relation of the latter to the regular parts of the machine; Fig. 2 is a fragmentary top plan view of the machine; Fig. 3 is a left side elevation partly in section of the particular portion of the machine where the present invention takes effect, this view representing the relation of parts when the so-called "split" has been established at a certain point and the operating handle of the machine has been drawn forward; Fig. 4 is a similar view illustrating the changed effect when the machine is "normal" or operating without a "split"; Fig. 5 is a front elevation of that department or section of the machine to which the present invention is applied, some parts being broken away to disclose others to the rear and some parts appearing in cross-section; Fig. 6 is a detail sectional view taken substantially on the line 6—6 of Fig. 5; Fig. 7 is a front elevation of indexing devices on the exterior of the machine; and Fig. 8 is a section on the line 8—8 of Fig. 7.

The present invention has to do particularly with that portion of the machine commonly termed the "printing section." In the regular Burroughs machine it is located at the rear and comprises suitable supporting side plates, pivoted hammers 715 striking rearwardly, pivoted hammer-driving levers 716 carrying studs 753 engaging cam slots 7 in the hammers, springs 780 attached to said levers and tending to impel them in a direction to deliver the hammer blow, pivoted latches 717 normally restraining said levers, pivoted spring-actuated pawls 718 for lifting said latches, an oscillating bail carrying said pawls and composed of side arms 711 and a cross rod 704, and a restoring bail for the levers 716, said bail comprising side arms 712 and a cross rod 709.

The numeral 611 designates the usual rack
